UNITED STATES PATENT OFFICE

RODERICK H. WILLCOX, OF COLUMBUS, OHIO, ASSIGNOR TO COLUMBUS COATED FABRICS CORPORATION, OF COLUMBUS, OHIO, A CORPORATION OF OHIO

DESIGN FOR A TABLE COVER OR SIMILAR ARTICLE

Application filed April 15, 1933. Serial No. 47,796. Term of patent 3½ years.

To all whom it may concern:

Be it known that I, RODERICK H. WILLCOX, a citizen of the United States of America, residing at Columbus, in the county of Franklin and State of Ohio, have invented a new, original, and ornamental Design for a Table Cover or Similar Article, of which the following is the specification, reference being had to the accompanying drawing, forming a part thereof.

The figure is a plan view of a table cover or similar article, showing my new design.

I claim:

The ornamental design for a table cover or similar article, as shown.

RODERICK H. WILLCOX.
